UNITED STATES PATENT OFFICE.

CHARLES VAN MIDDLESWORTH, OF BROOKLYN, NEW YORK, ASSIGNOR TO THE VAN DYCK GRAVURE COMPANY, OF NEW YORK, N. Y.

DROP-GUIDE AND OPERATING MECHANISM THEREFOR.

1,008,288.

Specification of Letters Patent.

Patented Nov. 7, 1911.

Original application filed November 23, 1908, Serial No. 464,096. Divided and this application filed October 15, 1909. Serial No. 522,752.

To all whom it may concern:

Be it known that I, CHARLES VAN MIDDLESWORTH, of Brooklyn, in the county of Kings, and in the State of New York, have 5 invented a certain new and useful Improvement in Drop-Guides and Operating Mechanism Therefor, and do hereby declare that the following is a full, clear, and exact description thereof.

10 My invention relates to an improvement in drop guides and mechanisms for operating the same in printing presses, and involves an arrangement whereby the drop guides may be raised at every revolution of 15 the printing cylinder or only at every alternate revolution thereof, as well as the detailed construction of the drop guides themselves.

This is a divisional application of my application for printing machines, Serial No. 464,096, filed November 23rd, 1908.

I have shown one embodiment of my invention in the accompanying drawings, in which—

25 Figure 1 is a side elevation of a printing press equipped with my invention; Fig. 2 is an enlarged view of the drop-guides; Fig. 3 is a detail view of the mechanism used for operating the drop-guides; Fig. 4 is a 30 plan view of the same; and Figs. 5 and 6 are details of the operating mechanism.

In the accompanying drawings, 1 represents a side standard for supporting the parts of the printing machine, only one of 35 these standards being shown in Fig. 1, although there is a similar standard on the other side of the machine. Supported in the standards there is an impression cylinder 3 having its journals 4 located in an eccentric sleeve 5 supported in the journal 40 bearings 6. The eccentric sleeve 5 has attached thereto an arm 7, to the end of which is attached a link 8 designed to connect the eccentric sleeve with a manually-operated

45 lever 9. The lower end of the lever 9 is pivoted at 10 to the side standard 1, while the other end of the lever is provided with a handle 11, so that the same may be conveniently moved to raise and lower the impression cylinder.

50 A feeding table 12 is adapted to be supported at its outer end from the standard, and at its inner end from the journals 5. This is accomplished in the following man-

ner:—The table has attached thereto on its 55 under face a supporting bracket 13, the table being pivoted to the same at 14 near the outer end of the table, while the inner end of the table is supported by means of an adjustable screw 15, screw-threaded in 60 an upright 16 of the bracket 13, and having its head located in contact with the under face of the table. The outer end of the bracket 13 is supported from the standards through the agency of links 16^a, one of which 65 is situated on either side of the printing machine. The links 16^a are connected at their lower ends to the standards by means of an integral bracket 17 projecting from each of the side standards. The inner end of the 70 supporting bracket 13 is supported directly upon the eccentric sleeve 5 at each end of the impression cylinder, as shown in Fig. 1, the bracket for this purpose being provided with a circular housing 18 surrounding the 75 eccentric sleeve 5. It will thus be seen that by the parts above described, a movement of the handle 11 effects a movement simultaneously either up or down of the impression cylinder 3 and the feeding table 12. 80 The supporting bracket 13 also supports journal bearings 19, located on either side of the impression cylinder, for a shaft 20, which carries a series of drop guides 21. The bearings 19 are situated in detachable 85 arms 22, which are bolted to the upper face of the circular housing 18 by means of the bolts 23. I prevent the shaft 20 from becoming displaced out of its proper position in a lateral direction, by inserting screws 24 90 in the journal bearings 19 so as to register with depressions or grooves located at these points in the shaft 20.

Each of the drop guides 21 comprises a bracket 25 having a split sleeve adapted to 95 surround the shaft 20 and be tightened upon the same by means of a screw 26 having a thumb-piece 27. In the end of the bracket 25 I support, by means of a journal bearing 28, a rod 29, the inner end of which is 100 screw-threaded so as to carry a milled nut 30, which nut 30 is situated in an opening 31 on the end of the bracket 25. A spring 32 is provided around the rod 29, between the journal bearing 28 and the milled nut 105 30, so as to press the milled nut 30 continually in a rearward direction against the bracket 25. The nut 30 is furthermore pro-

vided with an annular recess 33 in which a screw-threaded pin 34 is adapted to be projected and tightened so as to maintain the milled nut in its adjusted position. The 5 end of the rod 29 carries a depending arm 35, which is located in a vertical position. To this arm 35 is riveted a curved guide 36, the end 37 of which is directed toward the arm 35 in an angular direction. The end 10 37 of the curved guide 36 is, however, directed to a point on the arm 35 slightly above the end of the latter. In the downward position of the drop guide, the arm 35 is designed to rest against a tongue 38 which 15 extends from beneath the table 12, from which it is supported by means of a transverse strip 39; as shown in Fig. 2.

The shaft 20 carries a series of drop guides of the character described and the 20 table 12 carries a series of tongues 38 co-operating with said drop guides. It will now be observed that a movement of the handle 11 so as to raise or lower the impression cylinder 3, results simultaneously 25 in a corresponding movement of the drop guides 21 and the table 12 with its attached tongues 38.

Power is conveyed to the machine from a shaft 40 supported in the side standards. 30 This shaft 40 is connected by suitable gears with a shaft 41 also situated in the side standards. As these gears constitute no portion 35 of my invention, and as the understanding of the machine would be facilitated by their omission, I have left them out of the description of the machine. The shaft 41 carries the printing cylinder 41^a. The printing cylinder may be of any desired character. It may be a cylinder provided 40 with a planographic printing surface, or it may be provided with an intaglio or relief printing surface, but in the particular printing process which I make use of in connection with this machine, I use a 45 gravure etching as the printing surface.

Power is conveyed from the printing cylinder by means of a gear 42 situated upon the same, to the impression cylinder 3, which latter carries at 50 either end thereof a gear 43. There are, of course, two of the gears 42 to mesh with the two gears 43.

As above described, the machine would operate in such a manner as to print a sheet at every revolution thereof. I have so constructed my machine, however, that it may be adjusted so as to operate at every other revolution. When so adjusted, each sheet of paper will receive two impressions instead of one, thus deepening the tone of the 55 particular color being printed. The mechanism which I use for this purpose is constructed as follows:—A cam 100 is carried upon a stub shaft 101, which is carried in an extension 97 of one of the supporting 60 brackets 13. The said shaft 101 also car-

ries a gear 102 which meshes with another gear 103, situated upon an extension of the shaft 4 which carries the impression cylinder. The gear 102 is exactly twice the diameter of the gear 103, so that as a consequence, when the gears are in mesh a single rotation of the impression cylinder will produce a half revolution of the gear 102, thus requiring two revolutions of the gear 103 for each complete revolution of the gear 102. I have, however, made the shaft 4 sufficiently long so that the gear 103 which is carried upon said shaft and secured thereto by means of a spline 104 may be moved out of mesh with the gear 102 so as to disengage the shafts 4 and 101. When so moved the gear 103 will occupy a position such as shown in dotted lines in Fig. 4. As the paper is grasped by the gripper jaws, it is, of course, necessary to move the drop 85 guides 21 upwardly out of the path of the sheet of paper, and in order to effect this, I locate upon the end of the shaft 20, as shown in Fig. 4, a lever arm 105, which has a lateral extension 106 attached thereto by 90 means of a screw 107. The lever arm 105 is tightly secured to said shaft 20. The lateral extension 106 is adapted to be normally drawn downwardly by means of a spring 108, which is attached at its lower 95 end to any convenient support, such as rod 109. A bell-crank lever 110 is pivoted to the frame 97 upon a stub shaft 111. One end of this bell-crank lever 110 extends beneath the lateral projection 106. Here the said 100 lever 110 is curved to cause the extension 106 to always be tangent to the portion of the bell crank lever with which it contacts. Upon the same stub shaft 111 there is a depending lever arm 112 loosely carried upon 105 said shaft, the lower end of which carries a roller 113 designed to run upon a cam 114, tightly secured to the shaft 4. The lower end of the lever arm 112 is normally maintained in contact with the cam 114 by a 110 spring 112^a, which is attached thereto at one end and at the other end to a small bracket 112^b attached to the frame 97. The lever arm 112 is furthermore maintained from passing beyond one side of the bell-crank lever 110 by a projection 112^c, situated upon the lower end of the bell-crank lever 110 and projecting beyond the lever arm 112. 115 The lever arm 112 carries near its center a bushing 115, in the center of which is situated a longitudinally movable rod or plunger 116 having a pin 117 attached thereto and adapted to slide within a slot 118 in the side of said bushing. The lower end of the bell-crank lever 110 is provided with a 120 hole 119 aligning with the opening in the bushing 115. When the pin 117 is located at the inner end of the slot 118, as shown in Fig. 4, the plunger 116 is projected into the 125 hole 119, situated in the end of the bell- 130

crank lever 110. Any movement of the lever arm 112 in this position of the parts, therefore, causes a corresponding movement of the bell-crank lever 110. The plunger 116 is moved back and forth into and out of engagement with the hole 119 by the movement of the pin 117, which engages with the bifurcated end 119^a of a lever 120, pivoted at 121 to a bracket 122 carried upon the side 10 of the frame 97. The lever 120 has at its other end a roller 123, which runs within the cam 100, above referred to. When the plunger 116 is maintained at its innermost position, in which it engages the hole 119, the 15 rotation of the shaft 4, and as a consequence, the attached cam 114, causes the lever arm 112 to be moved in unison with the bell-crank 110. As a consequence, with each revolution of the impression cylinder the drop 20 guides 21 are raised at the moment that the grippers pass the edge or end of the feeding table 12. The parts operate in the manner described when the gear 103 has been moved into the position shown in dotted lines, and 25 the gear 102 is caused to remain stationary. When, however, the gear 103 is moved inwardly so as to mesh with the gear 102, during every other revolution of the gear 103, and as a consequence the impression 30 cylinder 3, the roller 123 is moved by the cam 100 into such a position that the pin 117 is caused to withdraw the plunger 116 from engagement with the hole 119, thereby 35 permitting the movement of the lever arm 112 without causing the movement of the bell-crank lever 110. In this position of the parts, therefore, the drop guides remain 40 stationary in their lowermost positions throughout every alternate revolution of the impression cylinder, as the raising of the drop guides is unnecessary and even disadvantageous during the times when it is not desired to feed additional sheets of 45 paper.

45 The operation of the machine in general is as follows:—In case it is desired to print each sheet with a single impression, the gear 103 is moved to the outermost end of the shaft 4 out of engagement with the gear

102. A sheet of paper is now fed down the 50 table 12 until it contacts with the ends of the drop guides 21. Then the paper is gripped by the grippers. Meantime, the drop guides 21 have been raised through the agency of the lever arm 112, which is actuated by the cam 114 so as to permit the edge of the paper to pass onward with the cylinder without any danger of tearing. In the case where it is desired to cause the sheet to be printed with a second impression, the 55 gear 103 is moved inwardly so as to mesh with gears 102.

I claim:

1. In a printing press, the combination of a printing couple for giving each sheet of paper a plurality of impressions, one or more guides for positioning a sheet of paper being fed to the press, and adjustable means for permitting the feeding of a new sheet of paper to the press at every impression made 70 therein or only at every other impression made therein.

2. In a printing press, the combination of a printing couple, one or more guides for positioning a sheet of paper being fed to the 75 press, a lever for actuating the same, a second lever adapted to operate said first mentioned lever, a cam for operating said second lever, and means for connecting said levers together only at every other impression made by the printing couple.

3. In a printing press, the combination of a printing couple, one or more guides for positioning a sheet of paper being fed to the 85 press, a lever for actuating the same, a second lever adapted to operate said first mentioned lever, a cam for operating said second lever, and means for connecting said levers together only at every other impression made by the printing couple, said means 90 being adapted to be adjusted to permit said levers to be permanently connected.

In testimony that I claim the foregoing I have hereunto set my hand.

CHARLES VAN MIDDLESWORTH.
